UNITED STATES PATENT OFFICE.

JOHN McCARTHY, OF PLAINFIELD, NEW JERSEY, ASSIGNOR TO THE AMERICAN WRITING MACHINE COMPANY, OF ILION, NEW YORK.

DESIGN FOR A HOOK FOR TYPE-WRITER INKING-RIBBONS.

SPECIFICATION forming part of Design No. 30,834, dated May 23, 1899.

Application filed April 18, 1899. Serial No. 713,518. Term of patent 14 years.

To all whom it may concern:

Be it known that I, JOHN McCARTHY, a citizen of the United States, and a resident of Plainfield, in the county of Union and State 5 of New Jersey, have invented and produced a new and original Design for Hooks for Type-Writer Inking-Ribbons, of which the following is a specification.

In the accompanying drawings, Figure 1 is 10 a plan view of a hook or fastening device embodying my design. Fig. 2 is a front edge elevation thereof. Fig. 3 is an end elevation of the same.

The leading feature of my design consists 15 of a cross-bar and hooks at the ends thereof. The hooks are formed as continuations of the cross-bar—that is to say, each end of the cross-bar 1 is bent backwardly at an angle, as at 2, then formed with a lateral bend, as at 20 3, then extended forwardly parallel with the portion 2, as at 4, and terminated in a taper-

ing and sharp point 5, as shown clearly at Fig. 1, where the compound hook or double-ended fastening device is shown on an enlarged scale.

The hook portions of the device are formed in the plane of the cross-bar, as shown at Figs. 2 and 3.

What I claim as new, and desire to secure by Letters Patent, is—

The design for a hook for type-writer inking-ribbons substantially as shown and described.

Signed at the borough of Manhattan, in the city of New York, in the county of New York 35 and State of New York, this 17th day of April, A. D. 1899.

JOHN McCARTHY.
